UNITED STATES PATENT OFFICE

PAUL R. SIMMONS, OF MARION, INDIANA, ASSIGNOR TO INDIANA FIBRE PRODUCTS COMPANY, OF MARION, INDIANA

DISH HOLDER

Application filed August 2, 1929. Serial No. 383,051.

This invention relates to a holder for dishes suitable for use in serving ice cream and the like and has reference in particular to the permanent holder associated with which is a removable and replaceable container fitted thereto.

The chief object of the invention is to provide a permanent holder for a dish of the aforesaid character which holder may be readily handled and cleaned and which will yieldingly retain a dish when inserted and yet permit ready and forcible detachment of the dish from the holder.

Dishes of the aforesaid character usually include a substantially flat base portion and a corrugated frusto-conical side and such a dish is illustrated in the prior Patent 1,356,409, dated October 19, 1920. The present invention contemplates the formation of the holder in an improved manner.

The full nature of the invention will be understood from the accompanying drawings and the following description and claims:

Fig. 1 is a top plan view of the holder embodying the invention. Fig. 2 is a central sectional view taken on the line 2—2 of Fig. 1 and in the direction of the arrows. Fig. 3 is an enlarged transverse sectional view of one of the retaining fingers taken on the line 3—3 of Fig. 2 and in the direction of the arrows. Fig. 4 is a similar view of a modified form of finger shown in Fig. 3.

In the drawings 10 indicates a base portion and 11 a neck portion of a holder. The bottom plate portion 12 includes a centrally depressed portion 13 that is receivable by the annularly grooved and locking portion 14 supported by the neck 11. Any other form for the uniting of the bottom plate portion 12 and the base portion 10 may be provided.

Extending upwardly in spaced relation with each other and about the periphery of the plate portion 12 and extending outwardly as well are a plurality of fingers 15, each of which is herein shown provided with a groove 16 and the outwardly extending torque portions 17 which are turned back as at 18 to form a protected edge for each finger also serve to reinforce the fingers. As shown in Fig. 3 the fingers gradually taper downward-

ly so that the groove 16 is gradually reduced as it approaches the plate 12. Preferably the several fingers are formed integral with the plate portion 12 and are formed from a flat sheet therewith.

In order to prevent escapement of the corrugated dish which is nestingly received by the fingers which are more or less spring like in character, a plurality of inwardly directed tips 19 are provided and herein the same are shown positioned diametrically opposite each other. Preferably these tips are not provided upon each finger. Each tip thus provided includes the dish-retaining projection so that when pressure is applied to the contents of the dish for the removal thereof, such as the insertion of a spoon in ice cream, it will not "jump" from the holder. The number of tips may be any number but at least two should be provided.

Instead of having each of the fingers formed of the material from which the bottom plate 12 is formed and integral therewith, each may be formed from a solid but fluted triangular rod, the cross section of which is shown in Fig. 4 and the lower ends of each of the rods or fingers of this character are welded, riveted or otherwise secured to the plate. The dotted lines in Fig. 3 and the numeral 25 indicate the side wall of the dish nestingly associated with the fingers.

While herein the fingers each are shown as comprise of a single inwardly-directed groove flanked by an inwardly-positioned tongue, the reverse arrangement may be employed with equal facility and the terminology "fluted" employed in the claims is intended to include both forms.

The invention claimed is:

1. A holder for truncated dishes and the like comprising a supporting base, a neck extending upwardly therefrom, a top carried by said base and extending outwardly from the neck and adapted to be engaged by the bottom of a dish, and a plurality of outwardly and upwardly inclined individual dish-nesting fingers carried by said top and secured thereto at the bottom of the fingers and arranged for nesting reception of the dish and having substantially full linear contact with

the side thereof from said top to the top of said finger.

2. A holder for truncated dishes and the like comprising a supporting base, a neck extending upwardly therefrom, a top carried by said base and extending outwardly from the neck, and a plurality of outwardly and upwardly directed individual dish-nesting fingers carried by said top and secured thereto at the bottom of the fingers, each finger having a fluted interior for nestingly receiving a corrugated element of the dish whereby rotation of the dish is prevented.

3. A holder for truncated dishes and the like comprising a supporting base, a neck extending upwardly therefrom, a top carried by said base and extending outwardly from the neck, a plurality of outwardly and upwardly directed individual dish-nesting fingers carried by said top and secured thereto at the bottom of the fingers, each finger having a fluted interior for nestingly receiving a corrugated element of the dish whereby rotation of the dish is prevented, and a plurality of inwardly directed dish retaining tip projections carried by the outer ends of a plurality of said fingers.

4. A holder for truncated dishes and the like comprising a supporting base, a neck extending upwardly therefrom, a top carried by said base and extending outwardly from the neck, a plurality of outwardly and upwardly directed individual dish-nesting fingers carried by said top and secured thereto at the bottom of the fingers, each finger having a fluted interior for nestingly receiving a corrugated element of the dish whereby rotation of the dish is prevented, a plurality of inwardly directed dish retaining tip projections carried by the outer ends of a plurality of said fingers, and a plurality of said fingers being free from said tip projections and the tipped fingers being positioned intermediate a pair of adjacent tipless fingers, all of said fingers being arranged in spaced relation about the periphery of the top.

In witness whereof, I have hereunto affixed my signature:

PAUL R. SIMMONS.
